UNITED STATES PATENT OFFICE.

JOHN SIEGFRIED KENDALL, OF HAMILTON, ONTARIO, CANADA.

IGNITION DEVICE FOR INTERNAL-COMBUSTION ENGINES.

1,146,800.

Specification of Letters Patent. Patented July 20, 1915.

Application filed August 3, 1914. Serial No. 854,761.

To all whom it may concern:

Be it known that I, JOHN SIEGFRIED KENDALL, of the city of Hamilton, in the county of Wentworth, in the Province of Ontario, Canada, have invented certain new and useful Improvements in Ignition Devices for Internal-Combustion Engines, of which the following is the specification.

My invention relates to improvements in ignition devices for internal combustion engines, and the object of the invention is to devise positive means for igniting the full charge in the cylinders of said engines, as opposed to the more or less inefficient methods at present employed.

The invention consists of the parts constructed and arranged as hereinafter more particularly described and illustrated in the accompanying drawings in which:—

20 Figure 1 represents a diagrammatic plan of my device with an elevation of the commutator and contacting device. Fig. 2 is a plan view of the aforesaid contacting device. Fig. 3 is an elevation of the contacting device. Fig. 4 is a detail of the main arm and pivot of the contacting device. Fig. 5 is a detail of the contact plate of the contacting device. Fig. 6 comprises an elevation and top and bottom plans of 25 the multiple spark plug. Fig. 7 represents a central vertical section through Fig. 6 with a cap shown partially in position on the spark plug. Fig. 8 is a plan view of the inside of the cap shown in section in 30 Fig. 7.

Like characters of reference indicate corresponding parts in the different views.

In Fig. 1, 1 is a battery supplying current to the primary winding 2 of the 40 induction coil. 4 is a contacting device in the primary circuit connected in series with the battery 1 and the primary winding 2 of the induction coil, and has in parallel across its terminals a condenser 5 adapted 45 to prevent sparking at the contacts. 7 and 8 are gear wheels having the ratio of 1 to 2 and the wheel 7 carries with it a quadruple cam 6 and turns at the same speed as the engine main shaft. This cam actuates the contacting device 4. The gear 8 has a commutator arm 9 mounted thereon and insulated therefrom, and this arm by rotation makes contact with each of the four contact plates 10, successively. In the 50 secondary circuit we have as our source of current the secondary winding 3 of the in-

duction coil. In series with this are connected the commutator arm 9, the spark plug 12 and the engine frame 11. On leaving the secondary winding 3 of the coil, the current passes to the commutator arm 9 where it is delivered to one of the four contact plates 10 and passes thence to the corresponding spark gap in the plug 12. Upon jumping the spark gap it is returned to the induction coil through the engine frame. The safety spark gap 13 is included in the circuit as a protection for the induction coil, in case the circuit is broken. The contacting device 4 in the primary circuit comprises 60 a T-shaped main arm 14, to the head of which is attached by screws 24 so as to be insulated therefrom by the plate 15, the right angled strip 16. Near the free end of this strip is located a small bearing wheel 65 17 to prevent the free end from wearing away by rubbing. The main arm 14 has a pin 19 located therein adjacent to its connection to the bent strip 16, and this pin is rigidly secured to the base plate 18. At 70 the opposite end of the arm 14 to that carrying the pin 19, is a contact screw 20 having a platinum point. Immediately opposite this screw, on the bent plate 16, is located another platinum contact. It will be easily 75 seen that as the cam 6 revolves each tooth thereon will engage the wheel 17 and push the plate 16 into contact with the point of the screw 20, thus closing the primary circuit. It is of course understood 80 that the contact device 4 must be timed to work synchronously with the commutator bar 9 and plates 10, otherwise the high tension impulses induced in the secondary circuit could never reach the spark plug. The 85 screw 20 may be adjusted to increase or decrease the gap between its point and the bent plate 16, by the lock nut 21 near its head. The quadruple cam 6 is retained on the end of its shaft by the screw 23 and 90 washer 22.

In Figs. 6, 7 and 8 my quadruple spark plug 12 is shown. 25 is the metallic casing of the plug, and is threaded at its lower end for connection to the engine cylinder. The four bent members 26 are secured to the casing 25 about its lower circumference and together with the four insulated conductors 27, form four separate and distinct spark gaps. 28 is a washer located where the area of the plug changes, and 29 is an insulating core retained with-

in the metal-casing of the plug by a threaded flange 30, composed of some insulating material. The flange 30 bears on the shoulder 31 of said insulating core and thus when screwed down into contact retains the same in position. 32 is a smooth fitting cap of insulation adapted to fit snugly over the top of the core 29. It contains four separate metallic pockets 33 into which the ends of the conductors 27 project when the cap is in position. Leads 34 pass from the aforesaid pockets out through the top of the cap to a four-strand cable 35, and this in turn is connected to the contact plates 10 of the commutator. The use of the cap 32 is obvious. It prevents short circuiting between the conductors 27 as the result of oil, etc., lodging there, and also prevents the accumulation of dirt. Another advantage it possesses is the simple and effective connection formed thereby between the cable 35 and plug 12.

The operation of my device is as follows:—When the engine is on dead center, and the stroke is just commencing, or possibly a little before this, the end tooth of the quadruple cam 6 engages the roller 17 on the contact plate 16, and presses the platinum point on said plate into contact with the platinum point of the screw 20. This closes the primary circuit, and the battery 1 will now cause a current to flow therethrough. At the same instant that contact is made between the plate 16 and the screw 20, the commutator arm 9 on the gear 8 will be in contact with the end contact plate 10. Thus the secondary circuit will also be closed if the spark gap at the plug is neglected. Since it is a high tension circuit this gap is negligible, and thus the high voltage induced in the secondary winding of the induction coil will be sufficient to bridge the gap in the spark plug and a spark will be produced. The operation above described will be repeated four times, namely as each tooth on the cam 6 engages the wheel 17. Since the teeth are all close together, the four sparks produced will occur one after the other in a comparatively early portion of the stroke. The sparks do not occur simultaneously, and hence a great advantage of my device is that each spark produced is the maximum size obtainable from the source of current at my disposal. In any four gap-plugs at present in use, this is not the case, the sparks occurring simultaneously, and hence being practically one spark split up into four correspondingly smaller ones. Also, in present systems of ignition it is customary to produce one spark early in the stroke, and trust to this to ignite the charge. As is well known the charge is highly compressed when this spark occurs, and in this condition it tends slightly to liquefy. This is not favorable to ignition, and hence a

miss is often the result. In my device the first spark occurs when the stroke commences, or slightly before. The charge may ignite at this point or it may not. If it does not the second spark has an opportunity to act. This process is repeated four times and the charge is ignited. Should the first spark fire the gas, it is quite possible that there may not be complete combustion, and in this event the piston will receive a fresh impulse as each spark occurs, due to some unburned gas taking fire at each spark.

In my drawings I have shown the apparatus arranged for igniting a single cylinder engine. This, of course, is intended to be duplicated as often as a cylinder is added, and it may be readily seen that my device is as easily adaptable to six cylinders as to one. The source of electric current is also shown diagrammatically as a battery of cells, used in conjunction with an induction coil. This is not intended to limit my device to a low tension source, as it may be applied equally well when drawing from low, intermediate or high tension, and whether supplied by batteries, coils or magnetos. The contacting device I employ may also be modified considerably without departing from the spirit of the invention, and the form shown is to be taken in an illustrative and not in a limiting sense.

From the foregoing description it is apparent that I have devised an ignition system which may be classed as positive, and one which for its added advantages requires no correspondingly greater attention.

What I claim as my invention and desire to secure by Letters Patent is:—

1. In an ignition device for internal combustion engines, the combination with the source of high tension current, of distributing means for each spark plug, a multiple spark plug producing successive sparks for each explosive stroke of the piston, and a plurality of mutually insulated conducting means connecting each spark plug with its distributing means.

2. In an ignition device for internal combustion engines, the combination with the source of high tension current, of distributing means for each spark plug, a multiple spark plug producing successive sparks in each cylinder as the result of such distribution, and a plurality of mutually insulated conducting means connecting each spark plug with its distributing means.

3. In an ignition device for internal combustion engines, the combination with the source of high tension current, of a suitably rotating commutator arm, contact plates over which said arm passes and with which it makes sliding contact, and a multiple spark plug with spark gaps to correspond in number with the number of said contact plates.

4. In an ignition device for internal combustion engines, the combination with the source of high tension current, of distributing means for each spark plug, a multiple spark plug with gaps which are adapted to spark in succession, and an insulation cap adapted to fit smoothly over the top of said plug and having multiple pockets therein into which the multiple conductors of the plug are designed to enter and make contact, said pockets having connection through the top of the cap with a multiple strand cable.

5. In an ignition device for internal combustion engines, the combination with the high tension circuit comprising the source of high tension current, distributing means for each spark plug, and a multiple spark plug producing successive sparks in each cylinder as the result of such distribution, of a low tension circuit comprising a low tension current source, means for producing a high tension current therefrom, a contacting device designed to intermittently close the circuit, and a condenser across the terminals of said contacting device.

6. In an ignition device for internal combustion engines, the combination with the secondary circuit comprising a source of high tension current, distributing means for each spark plug, and a multiple spark plug producing successive sparks in each cylinder as the result of such distribution, of a primary circuit comprising a low tension current source, means for producing a high tension source therefrom, a contacting device consisting of a multiple cam adapted to bring a platinum contact on a spring plate into engagement with the point of a contact screw, and a condenser connected to the terminals of said contacting device.

7. In an ignition device for internal com-

bustion engines, the combination with the secondary circuit comprising distributing means for each spark plug, a multiple spark plug with gaps which are adapted to spark in succession, and an insulation cap adapted to fit smoothly over the top of said plug, and having multiple pockets therein into which the multiple conductors of the plug are designed to enter and make contact, said pockets having connection through the top of the cap with a multiple strand cable, of a primary circuit comprising a low tension current source, means for producing a high tension source therefrom, a contacting device consisting of a multiple cam adapted to bring a platinum contact on a spring plate into engagement with the point of a contact screw, and a condenser connected to the terminals of said contacting device.

8. In an ignition device for internal combustion engines, the combination with the secondary circuit comprising a source of high tension current, a suitably rotating commutator arm, contact plates over which said arm passes and with which it makes sliding contact, and a multiple spark plug with spark gaps to correspond in number with the number of said contact plates, of a primary circuit comprising a low tension current source, means for producing a high tension source therefrom, a contacting device designed to intermittently close the circuit, and a condenser across the terminals of said contacting device.

In testimony whereof, I have signed at the city of Hamilton, in the county of Wentworth, in the Province of Ontario, Canada, this 30th day of July, 1914.

JOHN SIEGFRIED KENDALL.
